UNITED STATES PATENT OFFICE.

HAROLD G. BAXTER, OF BALDWIN, NEW YORK, ASSIGNOR TO WESTINGHOUSE ELECTRIC & MANUFACTURING COMPANY, A CORPORATION OF PENNSYLVANIA.

SNAP SWITCH,

Application filed August 30, 1920. Serial No. 406,843.

To all whom it may concern:

Be it known that I, HAROLD G. BAXTER, a subject of the King of Great Britain, and a resident of Baldwin, in the county of Nassau and State of New York, have invented a new and useful Improvement in Snap Switches, of which the following is a specification.

My invention relates to electric knife switches of the "snap" or quick-break type, and it has for its object the provision of a construction in which the movement of the switch blades from a completely-closed position to a wide-open position, or vice versa, is rapid.

In snap switches of the ordinary type, the spring which throws the switch blades is placed under increasing tension until such tension is great enough to move the switch blades. By reason of the fact that the force of the spring is continually exerted on the blades during the movement of the switch lever, sometimes the blades move before the full tension of the spring is brought to bear. Such movement is likely to be slow or intermittent, with the result that arcing takes place between the blades and the contacts.

By my construction, the blades are held against movement until the lever has been moved to its extreme position and the spring, consequently, placed under full tension. This arrangement permits the full force of the spring to be exerted on the blades at their starting position, where such force is most needed, and insures a rapid and complete movement by the blades from the one to the other of its extreme positions. In the particular embodiment of my invention illustrated in the accompanying drawing—

Fig. 1 is an elevation showing the switch in closed position, Fig. 2 is a view taken at right angles to Fig. 1, Fig. 3 is a detail view of the switch handle, and Fig. 4 is a detail view of the blade-carrying bracket, partially completed.

The switch is of the oscillating type and is mounted on the usual insulating base 3 which supports the terminals 4 and 5 connected to the contact members 6 and 7. Also mounted on the base 3, are the frame members 8 on which are carried the moving parts of the switch.

A pair of switch blades 9 are mounted on the shaft 10 and are insulated from each other either by suitable interposed insula-

tion or by making their connecting members of non-conducting material.

Also mounted on the shaft 10, is a spring 11 which, by pressing against opposite sides of the blade bracket 12 alternately, causes the blades to oscillate as hereinafter described.

For the purpose of placing the spring 11 under tension, to operate the blades, I provide a handle 13 having a bracket portion 14, the lower end of which abuts against one of the extensions of the spring 11—depending upon the direction in which the handle is being moved. The handle is pivotally supported on the frame 8 by pins 21 that extend through the holes 21a. The movement of the handle about the pivots 21 swings its lower end against one prong of the spring 11 and causes the other prong of the spring to abut against the blade bracket 12, thus tending to rotate the blades. The handle bracket 14 is slotted at 22 to allow passage of the shaft 10 therethrough and to permit movement of the handle on the pivots 21, without interference by the shaft 10.

In the upper portion of the handle bracket 14 is a U-shaped slot 15 registering with slots 16 in the frame members 8. Extending through the slots 15 and 16 is a pin 17 carrying the toggle members 18 which are pivoted at 19 to the members 20 and have rigid connection with the blades.

In Fig. 4, I show the blade bracket 12 punched, ready for bending to the proper shape. The bracket is bent to the form illustrated in Fig. 2. The portions 12a are provided with holes 23a through which rivets 23 extend to secure the blade members 9 thereto, the rivets being insulated from the blade members by rubber bushings, not shown, or otherwise. Holes 10a are provided to permit the mounting of the bracket 12 upon the shaft 10.

The operation of the device is as follows:

Starting with the parts in closed position, as shown in Fig. 1, the handle is moved to the right, causing the spring to exert pressure against the blade bracket 12. During the movement, the bracket 12 is prevented from rotating because the engagement of the pin 17 with the slot 15 holds the members 20 and toggles 18 against movement. When the movement of the handle is completed, the upwardly extending portion of the slot 15, at the left hand side of the handle 110

bracket, is in alinement with slots 16 of the frame members 8. The spring is then at its greatest tension, and the pin 17 is thrown upwardly into slots 16, thus releasing the 5 toggles 18 and allowing the spring to move the blades out of engagement with the contacts 6 and 7. The pivot 19 is moved to the extreme right and the pin 17 falls to its position of rest at the lower end of slot 16.

10 The switch is then in position for a closing movement in the reverse direction.

Various modifications may be made without departing from the scope of my invention, as set forth in the appended claims.

15 I claim as my invention:

1. In a switch of the class described, a base, a frame mounted on the base and provided with a slot; a pair of contacts also mounted on the base, an oscillating switch 20 blade pivoted in said frame, intermediate its ends, a spring for actuating said blade, a handle having a slot of U-shape and means connected therewith to put said spring under tension and cause it to impart rotative movement to the blade, the slot in the switch frame being positioned to register with one of the extensions of the U-shaped slot when the handle is at either of its limits of movement, a toggle member carried by the blade, 25 and a pin on said toggle member having slid-

ing engagement with the said slots and preventing movement of the blade until one extension of the U-shaped slot is in registry with the slot in the frame.

2. In an electric switch, the combination 35 with a movable contact member, of a supporting frame therefor, a tension device for actuating the movable contact member, a handle lever for placing the movable contact member under tension, a toggle connection between the handle and the movable contact member and means on the handle for preventing movement of the movable contact member until the handle has reached a predetermined position.

3. In an electric switch, the combination 40 with a movable contact member, of a supporting frame therefor, a tension device for actuating the movable contact member, a handle lever for placing the movable contact member under tension, a link connection between the handle and the movable contact member and means for preventing movement of the movable contact member until the handle has reached a predetermined 45 position.

In testimony whereof, I have hereunto subscribed my name this eleventh day of August, 1920.

HAROLD G. BAXTER.
